UNITED STATES PATENT OFFICE.

MANUEL D. DOMINGUEZ, OF NEW ORLEANS, LOUISIANA, ASSIGNOR OF ONE-HALF TO CHARLES A. DENIS AND ONE-HALF TO GEORGE SARPY, BOTH OF NEW ORLEANS, LOUISIANA.

ELECTRIC HAMMER.

Application filed April 26, 1924. Serial No. 709,260.

To all whom it may concern:

Be it known that I, MANUEL D. DOMINGUEZ, a citizen of Spain, and resident of New Orleans, in the parish of Orleans and

5 State of Louisiana, have invented certain new and useful Improvements in Electric Hammers, of which the following is a specification.

My invention relates to a class of implements or appliances which may be conveniently described as electric hammers, in which a heavy body is rapidly reciprocated by electrical means, and which are useful for hammering, riveting, chipping, caulking and analogous purposes.

The general object of the invention is to provide a tool or appliance of this class which is efficient, durable, easily controlled, and is as simple in structure as the desired 20 functions permit, and therefore can be manufactured at moderate cost.

The invention, in the preferred forms chosen for illustration, is embodied in a tool of moderate size which is therefore readily 25 portable and well adapted for "hand" use; but many or all of the structural features are also applicable or adaptable with or without reasonable modifications to larger and heavier tools in the class which may be conveniently described as non-portable, the 30 principal distinction being that such tools usually require, because of their weight, some supporting or guiding means other than the hands of the operator.

35 Broadly described, the invention comprises a casing having at one end a handle and at the other end a mounting for a tool or working element, which may be readily interchanged for different classes of work.

40 Within the casing is a reciprocable heavy piston or hammer suitably guided, and suitably disposed electro-magnetic means for impelling the hammer. Controlling mechanism, described for identification as intermittent controlling mechanism or means, may be provided exterior to the casing and to a certain extent independent of the tool; but in the present embodiments of the invention this intermittent controlling means

45 is enclosed in the casing, and is arranged to properly operate or vary the electro-magnetic circuits under the control of the moving hammer, to cause reciprocation thereof, whenever and so long as the main circuit 50 is closed. There is also provided arbitrary

or hand controlling mechanism, which may be designated for identification as the main control device or mechanism, to close and open the main circuit at the will of the operator in order to make the automatic or intermittent controlling mechanism effective. While this main control mechanism may be variously disposed, it is, in preferred constructions, as here shown, incorporated in the handle of the implement and is provided 55 with a trigger or finger piece projecting inwardly from the handle.

The characteristics and advantages of the invention are further sufficiently explained in connection with the following detail description of the accompanying drawings, which show certain exemplifying embodiments of the invention. After considering these embodiments, skilled persons will understand that many variations may be made 70 within the principles of the invention, and I contemplate the employment of any structures that are properly within the scope of the appended claims.

Fig. 1 is a top plan view of a tool or appliance embodying the invention in one form.

Fig. 2 is a side elevation of the same.

Fig. 3 is a view partly in side elevation and partly in longitudinal section, with one 85 of the cover plates removed.

Fig. 4 is a section at 4—4, Fig. 3.

Fig. 5 is a longitudinal section.

Fig. 6 is a detail view, partly in section, of one of the electro-magnets.

Fig. 7 is a sectional detail view of one of the magnet core or pole pieces showing the mode of attachment to the main frame or casing.

Fig. 8 is a detail view in side elevation 95 of the intermittent control mechanism or particularly the contact members thereof.

Fig. 9 is a view, partly in side elevation and partly in section, of the same.

Fig. 10 is a plan view of the main control or switch mechanism.

Fig. 10^a is a side elevation of the same.

Fig. 10^b is a transverse section.

Figs. 11, 12 and 13 are diagrammatic views showing different circuit arrangements, and with certain of the parts in positions especially chosen for explanatory purposes.

Fig. 14 is a view, mainly in longitudinal section, of a modified form of the appliance.

Fig. 15 is a section at 15—15, Fig. 14.

The electric hammer is built in, upon, or around a main frame or casing comprising side members 1, upper and lower end members 3 and 3^a, and movable or removable side plates 89—90, which have beveled edges 90^a fitting in grooves or rabbets 90^b, so that the cover plates may be easily removed by end-wise sliding. To facilitate such removal the 10 plates are provided with finger notches or sockets 93. Normally the plates are secured in closed position, to enclose and protect the mechanism, by screws 91.

At the lower end of the casing is a sleeve 2, arranged to receive with a reciprocating fit the stem 101 of the tool proper or working element 98. This tool has a flange 99 overlapping the end of sleeve 2, and is formed with an annular recess 100 of substantial length, in which fit the two legs of a split pin 102. These legs also engage in holes in the sleeve. In this way the tool 98 is removably held in position and permitted to have the necessary reciprocatory movement, and such movement is definitely limited. To facilitate removal of the cotter or split pin 102, a longitudinal groove or notch 103 is formed in sleeve 2.

Within the casing is the piston or hammer 16, usually formed of a suitable magnetic metal, such as steel or preferably, for magnetic reasons, of soft iron. If necessary or desirable, the hammer may have hardened end pieces, which may or may not be detachable. The hammer is provided with lugs 17, 17', 18, 18', each of which has a bushing 19, slidably fitting a guide rod 20. Desirably there are two of these guide rods equally spaced and located near opposite sides of the 30 casing. The lower end of each rod fits in a hole 21 in the lower end piece 3^a, and is secured by a pin 23. The upper end of each rod is formed with a portion 22 of reduced diameter fitting in a socket in the upper end piece 3.

The lower end of the hammer is arranged to strike the inward end 101 of the tool 98. The upper end of the hammer is arranged to strike a plate or thick washer 38, arranged for reciprocation in the lower portion of a spring sleeve or casing 4 formed at the upper end of the main casing. A heavy spring 39 is located in this sleeve or housing and bears at one end against the housing end 6, and at the other end against the plate 38. This arrangement takes up the shock of the hammer return stroke and also materially aids in speeding the hammer on its working stroke in an obvious way.

60 A suitable plurality of electro-magnetic devices is located within the casing about the hammer. Specifically, in the present embodiment, there are three pairs of these devices, each of which is an electro-magnet comprising a core body 11 (Figs. 6 and 7)

terminating in a pole piece or member 12, having a substantially part-cylindrical contour to closely fit around a segment of the hammer with suitable clearance. The core members are secured against suitable base 70 plates 10 and held to the side plates of the main casing or frame by screws 14. A suitable solenoid 13 is placed around each core 11. The three pairs of electro-magnets are equally spaced throughout the length of 75 the casing, one pair being located near each end and the other at the middle, as clearly shown in Figs. 3 and 5. Various suitable windings and connections for the solenoids are sufficiently indicated in Figs. 11, 12 and 80 13, the winding or wiring arrangement shown in Fig. 11 being preferred in some cases.

For the automatic or intermittent control of the hammer, a slider, block or contact carrier 24, is mounted for reciprocation on one of the guide rods 20. This contact carrier is located between two of the hammer lugs, such as 17 and 18, and is actuated by them. The block proper is of metal or insulating material, and may consist of two pieces 25, 25' and it is provided with a bushing 26 fitting around the guide rod. Contact fingers or blades 28, electrically connected, project from opposite sides of the block 24. One of the contact blades moves between parallel fixed contact blades or strips 31, each of these being continuous, and the other contact finger or blade 28, moves between the pairs of fixed contact strips 29, the confronting ends of the strips or blades of each pair being separated by a gap slightly shorter than the length of the moving contact 28, as clearly shown in Figs. 8 and 9. The tips of the blades 29, and 95 also the edges of the moving blade 28 which co-operates with these spaced contact blades, may be provided with tips such as 32 and 33 of hard metal which is resistant to the effects of arcing, so that the blades or contacts proper may be of a suitable material, such as copper or brass. All of the fixed contact blades or strips are secured by brackets 34, 34' to suitable supports, which 100 may be certain of the magnetic pole pieces, 115 suitable insulating bushings or other means being provided to insulate the contact blades or strips.

Arms or extensions 7 from the upper end 120 of the spring housing 4 carry a casing or housing 9, which is the handle of the appliance and desirably has at least one removable cover plate 94, secured by screws 95, 96, 97. The upper wall of the handle housing is formed with lugs or flanges 67, 68, which co-operate with flanges 42, 42' formed on the ends of an insulating block 41, Figs. 3, 10, 10^a and 10^b. This block carries the main control or switch mechanism. A conductor 43 secured to block 41 has a 125 130

binding post 45 to which one of the line conductors 66 is secured. At the other end of the conducting strip is a binding post 44 to which one of the main internal leads or 5 conductors 71 is secured. On the insulating block is also secured a conducting strip 48 of spring metal suitably bent to form a trigger arm and provided with a flange 53 fitting in a slot in trigger piece 54 of metal or 10 insulating material, which projects through a slot in the inward wall of the handle housing and is formed in arcuate shape to fit the finger of the operator. The contact blade 51 is secured to the trigger arm or may be 15 integral with flange 53. At one end of the trigger arm or conductor strip 48 is a binding post 50 to which the other line wire 65 is connected. Secured also to the insulating block 41 are spring contact fingers 57 to 20 co-operate with the blade 51. The contact fingers are in electrical connection with a binding post 60 to which the other internal main wire or conductor 72 is secured.

When the trigger piece 54 is pressed inward, the main circuit is closed in an obvious way, and the circuit is broken by the action of the spring arm whenever the trigger is released.

The line conductors 65 and 66 are arranged 30 in the form of an ordinary flexible double cable which passes through a rubber block 69 in an extension of the handle housing, and this rubber block holds the cable with sufficient firmness to prevent dislocation of 35 the conductors from their binding posts. The cable is guarded against kinking or breaking by a helical wire 70, one end of which is secured in the rubber block.

The internal main wires 71 and 72 pass 40 downward through a conduit formed in an extension 5 of one of the handle supports and spring housing 4 to a point where they enter the main casing. The internal main wires are then suitably branched and connected, as shown in the diagrams Figs. 11, 45 12 and 13. Specifically, wire 71 is branched to connect with all of the solenoids 13 toward one side of the casing, and each of 50 these solenoids is cross-connected to the opposite one of its pair, the windings being suitably arranged to provide the proper polarities of the pole pieces 12, as indicated in 55 the diagram. A conductor 81 goes from the left hand solenoid of the center pair, as viewed in Fig. 11, to one end of the continuous contact strips 30, and the other end of these strips is connected to the main internal wire 72, so that the center pair of 60 magnets is always energized. From the left hand solenoid of the lower pair of magnets, a conductor goes to the upper pair of spaced fixed contacts 29. The fixed and 65 movable contacts are shown in these diagrammatic views in an arbitrary or false position, for the sake of illustrative clear-

ness, although they could be so arranged in some practical embodiments of the invention. For the same reason the hammer 16 is shown provided with an upwardly extending stem 40, and the lugs 17 and 18, 70 which are actually connected to the hammer, are shown as connected to the stem in properly spaced relation to co-operate with the movable contact blades 28, which are shown in the diagrams as slidably mounted 75 on the stem. From the left hand solenoid and the upper pair of magnets, a conductor goes to the lower pair of spaced contacts 29.

Whenever the main circuit is closed, if the hammer is in an upper position, as 80 shown in Fig. 11, the lower pair of magnets is energized by contacts 28 closing the main circuit across the upper contacts 29 and contacts 30. The center magnets are always energized, and the hammer is pulled down 85 by strong electromagnetic force and strikes a blow upon the inward end of the tool or working element 98. Before the hammer reaches the end of its active stroke, lug 17 strikes the movable contacts 28 (or actually 90 the contact block 24, Fig. 8) and moves the contacts downward. As one of the contact members 28 bridges the gap between the upper and lower fixed contacts 29 all of the magnets are energized for a brief instant, 95 and thereafter the lower magnets are de-energized, and the upper magnets are energized in an obvious fashion as the moving contacts 28 close the main circuits between the lower fixed contacts 29 and contacts 30. 100 The hammer is then impelled upward in an obvious way; near the end of its upward or return stroke the circuits are again varied or reversed in an obvious fashion; the kinetic energy of the hammer is absorbed by 105 the spring-controlled abutment plate 38; the recoil of the spring aids in speeding the hammer on its next active stroke; these operations are repeated indefinitely as long as 110 the main circuit is closed.

Fig. 12 shows a different method of winding the solenoids and connecting them, which is preferred in some cases.

Fig. 13 shows that the hammer may in 115 some cases be guided in a sleeve or cylinder 16', which may or may not be of insulating material, located between the magnet pole faces.

Figs. 14 and 15 show a modified structure or arrangement in which the main housing or casing 76 may be of cylindrical form and is provided at its upper end with an extension 77 enlarged laterally to provide conductor chambers or passages 78 and 79. The handle 9 is formed on or secured to the upper end of the extension 77, substantially as in the previous example, and arbitrary or main switch mechanism is provided in the handle, as also previously explained. A 120 sleeve 148 of brass or other suitable non- 125 130

magnetic metal is located simply in the main casing. At its upper end the sleeve is provided with an annular flange 150 forming a seat for an upper sleeve 55, the upper 5 end of which rests in a socket formed by an annular flange 110 in the top plate 6 adjacent the handle.

Solenoids 153 and 154 wound on suitable 10 spools or otherwise suitably constructed and arranged, are placed in suitably spaced relation within the main casing and around sleeve 148 and are properly separated by blocks or spacers 75. The upper magnet spool rests against flange 150, and the lower 15 spool is engaged by a plate 83 which fits within the lower end of the casing and has about its central aperture, a socket 84 in which rests the lower end of sleeve 148. The lower end of the casing is closed by a cap 20 115, which has at its outer periphery a screw thread flange 116 in engagement with the screw thread end of the casing, and at its center the cap is formed with a sleeve 117 projecting within the sleeve 148. A 25 compressible gasket 118 of rubber or other suitable material is placed between the cap and plate 83 adjacent the periphery of the latter for the double purpose of retaining in position the described parts, namely the 30 sleeves 148 and 55, magnet spools or solenoids 153 and 154, and the plate 83, and to form a moisture-proof seal at the lower end of the casing. An extension 119 is centrally formed on cap 115 to receive and retain a 35 suitable tool, such as 184, substantially in the same manner in which the total or working member 98 is held in sleeve 2 in previously described constructions. In the present instances the working implement 184 is 40 a chipping or caulking tool.

The piston or hammer 43 is located with a 45 sliding fit in sleeve 148. The sleeve has at its upper end a head 149 and a spring 52 is located between this head and the upper end of the hammer, with a washer 51 interposed between the spring and the hammer when necessary or desirable. Since the hammer moves in what is practically a closed cylinder, longitudinal channels 144 are provided 50 in the periphery of the hammer to permit air to pass from one end of this cylinder to the other, and so to avoid any pneumatic impedance of the hammer movement. A stem 40 extends upward from the hammer through 55 an aperture in sleeve head 149, this stem corresponding substantially to the arrangement described in connection with diagrammatic Figs. 11 to 13. On an upper part of the stem, within the chamber formed by 60 casing extension 77, are spaced discs or flanges 17 and 18, and a contact member 165 of insulating material or else suitably insulated from the stem, is arranged to slide between the flanges.

65 Spring contact blades or fingers 162 elec-

trically connected, extend from the contact member and terminate in contact buttons 163 of hard metal resistant to the effects of arcing.

Secured within the upper sleeve 55, and 70 insulated from it by strips of suitable insulating material are channel contact strips 156, 157 and 158, of which the strip 156, located on one side of the sleeve is continuous, and the other strips 157 and 158 located in 75 line with each other at the other side of the sleeve are discontinuous and their adjacent ends are separated by insulating material 159, which may be a part of the insulating strip on which the contact members rest. 80

One of the main internal conductors 166 leading from the switch mechanism controlled by trigger 54 is connected to a binding post 167 at the upper end of contact strip 156. The other main internal conductor 172 is suitably branched and connected to ends of the solenoid windings. The other end of one of the solenoids is connected to a binding post 161 which is in electrical connection with contact strip 158, and the other 90 end of the other solenoid winding is connected by a conductor 168 to a binding post 169, which is in electrical connection with contact strip 157.

Whenever the main circuit is closed, if 95 the hammer is in an upper position, as shown in Fig. 14, the lower solenoid 154 is energized and the hammer is drawn smartly downward and strikes a blow on the inward end of the tool. Somewhat before the hammer strikes flange 17, stem 40 strikes contact carrier 165 and moves it downward so that the circuit including contact strip 157, is broken and the circuit is established between strip 156 and strip 158, and thereupon the 100 upper solenoid 153 is energized and attracts the hammer. Near the upper end of the hammer movement the circuit is again reversed in an obvious way and the hammer momentum is yieldably absorbed by spring 110 52, and the reextension of the spring aids in speeding the hammer on its next downward stroke; these operations are repeated indefinitely.

Provision may be made for lubrication 115 at important points. For instance, the slider or contact carrier 24, Fig. 3, may have an oil hole 27 and oil holes α , α' may be provided in lugs 17, 17', 18 and 18', Fig. 5.

Provision is also made for insulating parts 120 where necessary or desirable by means of strips of insulation and insulating bushings, some of which are referred to and others are not mentioned, since they may be provided as usual in electrical constructions 125 or arrangements.

What I claim is:—

1. An appliance of the class described, comprising a casing, a plurality of electromagnets disposed longitudinally therein, 130

- longitudinal guide rods adjacent opposite casing walls and detachably secured in the casing, a hammer arranged to reciprocate in the casing, and lugs thereon having sliding engagement with the guide rods.
2. An appliance of the class described, comprising a casing, a plurality of electro-magnets disposed longitudinally therein, longitudinal guide rods adjacent opposite casing walls and detachably secured in the casing, a hammer arranged to reciprocate in the casing, lugs thereon having sliding engagement with the guide rods, a contact carrier mounted for reciprocation on one of the guide rods between two of the hammer lugs, contacts on the carrier, and fixed contacts cooperating therewith.
3. An appliance of the class described, comprising a casing, a plurality of electro-magnets disposed longitudinally therein, longitudinal guide rods adjacent opposite casing walls and detachably secured in the casing, a hammer arranged to reciprocate in the casing, lugs thereon having sliding engagement with the guide rods, a contact carrier mounted for reciprocation on one of the guide rods between two of the hammer lugs with provision for lost motion, contacts on the carrier, and fixed contacts co-operating therewith.

Signed at New Orleans, in the parish of Orleans and State of Louisiana this 19th day of April A. D. 1924.

MANUEL D. DOMINGUEZ.
